FISH LURE

Jim C. Meador, Shreveport, La.

Application August 5, 1957, Serial No. 47,234

Term of patent 14 years

(Cl. D31—4)

The fish lure is illustrated in the drawing as it will appear while being trolled or retrieved.

I claim:

The ornamental design for a fish lure, substantially as shown and described.
